WARP STOP MECHANISM FOR LOOMS.

Application filed May 14, 1928. Serial No. 277,487.

This invention relates to warp stop mechanisms for looms and is more particularly directed to warp stop mechanisms of the transversely movable toothed detector bar type.

In warp stop mechanisms of the general type above mentioned there are a series of drop wires normally supported by the warp threads during weaving and such drop wires may be arranged in any desired number of banks. The drop wires are so associated with the toothed detector bars that when a warp thread breaks or becomes too slack, the drop wire will enter between the teeth 15 of the detector bars and effect loom stoppage.

One of the difficulties experienced in warp stop mechanisms of this general type is the fact that the fallen drop wire does not give clear notification of the location of the warp fault and much time is lost by the loom attendant in piecing up broken ends. The drop wires in a bank hang upon the warp threads close together and it is consequently desirable on the occurrence of a warp fault 25 that the drop wires, and, perchance, the threads of the sheet of warp, be separated at the point of warp breakage, and that the drop wire itself be deflected from the vertical plane in which it normally hangs that it may, by its bodily movement laterally and by its deflected position, separate the warp threads and unerringly locate the warp fault.

A difficulty that is frequently experienced in the transversely movable detector bar type of warp stop mechanism is that on the occurrence of a warp fault, the drop wire itself is displaced upwardly from its fallen position by the teeth of the detector bars engaged by it, and therefore neither effects loom stoppage nor locates the warp fault.

With the above facts in mind, the present invention relates more particularly to the correlated features of the fixed and transversely movable toothed detector bars and drop wires, whereby, on the occurrence of a warp fault, the released drop wire will not be upwardly displaced by the engaged detector bar teeth but will be moved laterally and deflected from its normally straight vertical position by the cooperating action of the teeth of the fixed and movable detector bars.

The invention and new features thereof will best be made clear from the following

description and the accompanying drawings 55 of a good form thereof.

In the drawings:

Fig. 1 is a perspective view of a portion of a warp stop mechanism of the transversely movable toothed bar type containing 60 the present invention;

Fig. 2 is a side elevation of portions of the fixed and movable detector bars showing a drop wire as having been released by its warp thread and resting upon the flat upper 65 surface of the fixed detector bar tooth;

Fig. 3 is a similar view showing the relation of parts when the released drop wire has fallen between the teeth of the detector bars;

Fig. 4 is a view similar to that of Figs. 2 and 3, showing the drop wire as engaged and moved laterally by the tooth of the movable detector bar; and

Fig. 5 is a view similar to that of Fig. 4, 75 showing the relation of parts when the movable detector bar has been arrested by the fallen drop wire.

Warp stop mechanisms of the transversely movable toothed detector bar type usually 80 comprise one or more fixed toothed detector bars and a movable toothed detector bar, and such transversely extending detector bars are supported in brackets at the sides of the loom and the movable detector bar is connected to suitable actuating mechanism for imparting thereto its transverse movement. These general essentials of a transversely 85 movable detector bar type of warp stop mechanism may be embodied in various 90 specific structures, but in the present instance of the invention the general warp stop mechanism is shown as substantially the same as that described in the Davis and Johnson Patent, No. 1,538,625, May 19, 1925, 95 to which reference may be had.

Referring more particularly to Fig. 1, the loom frame may be of any usual structure and at each side thereof have mounted thereon the side supports or brackets for the support of the warp stop mechanism. In the present instance, the loom frame 1, only a small part of which is indicated in Fig. 1, has adjustably mounted thereon the side brackets 2, one at each side of the loom, from 100 which rises the flange 3. Secured to the flange 3 of the bracket is the side support 4 105 which may be of any usual and appropriate

construction for sustaining the parts associated therewith. In the present instance these parts are indicated as being substantially the same as those of the Davis and Johnson patent, above mentioned.

Extending from the supports 4 are the lugs 5 in which is mounted the rock shaft 6 which may be actuated or rocked by an arm 7 connected to the downwardly extending rod 8 reciprocated from any usual going part of the loom. The rock shaft 6 has a series of rockers 9 on which are mounted the actuators 10. The actuators 10, of which there may be any suitable number in accordance with the number of banks of drop wires, are mounted upon the rocker or rockers for normal movement therewith but capable of having relative movement.

The rockers 9 and the actuators 10 may be substantially as more fully shown and described in the Davis and Johnson patent, it being understood that the actuators 10 are connected yieldingly to the rocker element or elements by a spring 11, with the result that if the actuator 10 is arrested in its movement with the rocker or rockers it may tilt relatively thereto on one of its fulcrums 12, substantially as described in the Davis and Johnson patent.

Pivotedly supported upon the rocker 9 at 13 is a finger 14, and at a point opposite the finger 14 there is a pivotal connection 15 with the associated actuator 10, in which respect the details of such mechanism may be the same as in the Davis and Johnson patent.

Extending beneath the series of fingers 14, of which there are a number corresponding to the number of actuators 10, is an arm 16 which bears upon the plunger 17 associated with a flexible sheathed wire 18, substantially the same in all respects as described in the Davis and Johnson patent, and for which reason further detailed description appears to be unnecessary.

The fixed or stationary toothed detector bar 19 is secured to the side supports 4, one at each side of the loom, as indicated in Fig. 1, and if desired the fixed detector bar 19 may be slotted longitudinally, as usual, for the reception of the transversely movable detector bar 20. Any appropriate construction of means for associating the movable and fixed detector bars may be employed, but that indicated and generally described as above forms a good practical embodiment of this feature.

Each of the movable detector bars 20 is connected to its associated actuator 10 by means of a link 21, the result being that upon rocking movement of the rock shaft 6, the actuators 10 will cause the movable toothed detector bars 20 to be moved transversely of the loom, as usual in this general type of warp stop mechanism.

Extending between the side supports 4, one at each side of the loom, are warp supports 22, and, as usual, there may be any appropriate number of these warp supports and they may be constructed and connected to the side supports in various ways so far as the present invention is concerned.

As will be indicated from Fig. 1, the drop wires 23 are arranged in a suitable number of banks and each bank is associated with a fixed and movable toothed detector bar. In the present instance of the invention the drop wires are indicated as having elongated slots 24 at their upper portions and through the elongated slots 24 of each bank 80 of drop wires the toothed detector bars pass. Each of the drop wires 23 is likewise provided with a warp engaging portion 25 and, in the present instance of the invention, the warp engaging portion 25 is constituted as a hole or opening formed in the drop wire, through which a warp thread passes. It is obvious, of course, that various forms of drop wires and warp supporting features thereof may be employed in the present invention.

As indicated in Figs. 2 to 5 inclusive, the fixed toothed detector bar 19 is provided with a series of wedge-shaped teeth 26, the side edges 27 of which diverge upwardly and form the flat drop wire supporting upper surface 28 on the teeth of the fixed detector bar.

The movable toothed detector bar 20 is provided with wedge-shaped teeth 29, the side edges 30 of which diverge downwardly. Each of the teeth 29 of the transversely movable detector bar has a flat drop wire supporting surface 31, as indicated in Figs. 2 to 5, which projects above the flat drop wire supporting upper surface of the fixed detector bar teeth 26.

Thus, as more clearly indicated in Figs. 2 to 5, the reversely arranged wedge-shaped teeth of the fixed and movable detector bars have their co-acting or adjacent inclined edges parallel throughout the length thereof extending continuously from the flat top drop wire supporting surface of each tooth to the bottom thereof, and, as shown, the teeth 29 of the transversely movable detector bar extend above the flat top surface of the teeth of the fixed detector bar.

On the occurrence of a warp fault, the released drop wire may at times during the relative movement of the detector bars, drop between the teeth thereof, or it may drop onto the flat top supporting surface 28 of a tooth of the fixed detector bar, as in Fig. 2, and be held raised. In this latter case the drop wire 23 will be moved laterally by a tooth of the movable detector bar, which extends above the top of the tooth of the fixed detector, and during such lateral movement of the released drop wire, it will en-

gage the adjacent drop wires in its path of movement and push them in the same direction along with the associated warp threads, thus effectively opening the warp. On the other hand, the released drop wire may fall upon the top supporting surface of a tooth of the transversely movable detector bar, with the result that it will be held from lateral movement by the adjacent drop wires while the moving tooth passes and then be permitted to fall either between the teeth of the fixed detector bar, as in Fig. 3, or onto the flat top supporting surface thereof, as in Fig. 2, with the result, in the latter case, on the return movement of the movable detector bar, the released drop wire and the adjacent drop wires will be moved laterally by the moving tooth and effect lateral separation of the warp threads.

20 When a released drop wire falls between the teeth of the movable and fixed detector bars in position to effect loom stoppage, it is important that it shall not be lifted again as it is engaged between the teeth, and to this end the angular inclination of the sides of the wedge teeth on the movable detector bar, which engage and move the released drop wire laterally, is such that while the drop wire will be given a bodily deflection when clamped between the inclined surfaces of the teeth, there will be no tendency to lift the released drop wire from its dropped position.

This feature of the invention is more clearly indicated in Fig. 4, wherein the line *a* represents a vertical plane passed through the bottom terminal end of an inclined edge of one of the movable teeth 29. The angle *b*, subtended between the vertical plane *a* and the inclined edge 30 of the movable tooth, is less than 45°. This may be otherwise stated, to the effect that the angle *c* between the inclined edge 30 and the horizontal base of the tooth is greater than 45°, the result being that when a drop wire is engaged by the inclined edge 30 of a movable tooth, as indicated in Fig. 4, and is moved laterally, there will be no tendency of the inclined pushing edge to lift the released drop wire.

As further insurance against upward displacement of the released drop wire as it is engaged between the teeth of the detector bars, each of the drop wires 23 has a tooth-engaging portion 32 which may be of less height than the inclined upwardly diverging side edge of the teeth of the fixed detector bar, the result being that when a drop wire is engaged between a tooth of the fixed detector bar and a tooth of the movable detector bar and is moved laterally to separate the warp, the top of the portion 32 of the fallen drop wire will be below the top of the wedge-shaped tooth of the fixed detector bar.

65 In other words, the top of the fixed tooth as

it inclines upwardly and divergently, will overlie the top of the portion 32 of the fallen drop wire and prevent or lock it from upward movement as the drop wire itself is moved laterally by the movable detector bar and finally clamped between and deflected by the co-acting inclined edges of the movable and fixed teeth of the detector bars.

This feature of the invention is important because when the drop wire is moved laterally by the movable detector bar, it is caused to move a number of drop wires and their associated warp threads, so that a lock to prevent upward movement of the released drop wire as it is moved laterally by the movable detector bar insures loom stoppage and final location of the warp fault by the separated drop wires and warp threads and the deflected drop wire clamp between the inclined surfaces of the cooperating teeth.

What is claimed is:

1. In a warp stop mechanism, the combination of a fixed detector bar having wedge shaped teeth the side edges of which diverge upwardly at a small angle to the vertical and are provided at their upper ends with flat drop wire supporting surfaces, a transversely movable detector bar having wedge shaped teeth provided with flat upper drop wire supporting surfaces and downwardly diverging inclined edges that form a small angle to the vertical and are longer than the side inclined edges of the fixed detector bar teeth, and a series of drop wires having teeth engaging portions adapted to be clamped between the inclined edges of the teeth to deflect a fallen drop wire.

2. In a warp stop mechanism, the combination of a fixed detector bar having wedge shaped teeth the side edges of which diverge upwardly and are provided with flat drop wire supporting upper surfaces, a transversely movable detector bar having wedge shaped teeth with downwardly diverging edges inclined at substantially less than 45° to a vertical plane passed through the terminal of the inclined edge and adapted to engage and move a drop wire against a fixed tooth without exerting an upward wedging action upon the wire, and a series of drop wires having teeth engaging portions adapted to be clamped between the inclined edges of the movable and fixed teeth.

3. In a warp stop mechanism for looms, the combination of fixed and movable detector bars, each having wedge shaped teeth provided with flat upper drop wire supporting surfaces and edge portions inclined at substantially less than 45° to a vertical plane passed through the terminal portion of the edge and adapted to grip a drop wire without exerting an upward wedging action upon the drop wire, and a series of drop wires through which the detector bars pass.

4. In a warp stop mechanism for looms,

the combination of a series of drop wires normally supported by the warp threads during weaving, a transversely movable detector bar having wedge shaped teeth with side edges diverging downwardly at an angle substantially less than 45° to a vertical plane passed through the terminal portions of said edges that a fallen drop wire may be moved laterally and not raised or subjected to an upward wedging action by said teeth, and a fixed detector bar having wedge shaped teeth provided with upwardly diverging side edges parallel to the side edges of the movable teeth and flat upper drop wire supporting surfaces.

5. In a warp stop mechanism for looms, the combination of a series of drop wires normally supported by the warp threads during weaving, a transversely movable detector bar having wedge shaped teeth the side edges of which diverge downwardly at an angle less than 45° to a vertical plane passed through the terminal portions of said edges that a fallen drop wire may be moved laterally and not raised or subjected to an upward wedging action by said teeth, and a fixed detector bar having wedge shaped teeth provided with upwardly diverging side edges parallel to the side edges of the movable teeth and flat upper drop wire supporting surfaces of less height than the movable detector bar teeth.

6. In a warp stop mechanism for looms, the combination of a fixed detector bar having wedge shaped teeth, the side edges of which diverge upwardly and form horizontal drop wire supporting surfaces between the upper ends of the side edges, a transversely movable detector bar having wedge shaped teeth, the side edges of which converge upwardly forming horizontal drop wire supporting surfaces higher than the drop wire supporting surfaces of the fixed detector bar teeth, said teeth being adapted 45 to grip a drop wire between their inclined edges without exerting an upward lifting action upon the drop wire and a series of drop wires through which the toothed detector bars pass.

50 7. In a warp stop motion of the trans-

versely movable toothed detector bar type, the combination of a fixed detector bar having wedge shaped teeth the side edges of which diverge upwardly, a transversely movable detector bar having wedge shaped teeth that diverge downwardly at a small angle to the vertical, and a series of drop wires through which the detector bars pass having tooth engaging portions of less height than the wedge shaped teeth of the fixed detector bar so that when a fallen drop wire is moved by a tooth of the movable detector bar into engagement with an inclined edge of a tooth of the fixed detector bar the top of the drop wire tooth engaging portion will be below the top of the wedge tooth of the fixed detector bar and be prevented from moving upwardly as it is deflected by the teeth of the detector bars to locate the warp fault.

8. In a warp stop motion for looms, the combination of a series of drop wires having teeth engaging portions, a movable detector bar having wedge shaped teeth that diverge downwardly at a small angle to the vertical, a fixed detector bar having wedge shaped teeth that diverge upwardly to a greater inclined height than the teeth engaging portion of a fallen drop wire to overhang the top of said portion of the drop wire and prevent upward movement of the drop wire as it is moved and deflected by the teeth of the detector bars to locate the warp fault.

9. In a warp stop mechanism for looms, the combination of a series of drop wires having teeth engaging portions, a fixed detector bar having wedge shaped teeth, the side edges of which diverge upward and terminate with flat top supporting surfaces between them on which a released drop wire may be supported, a movable detector bar having wedge shaped teeth of greater height than the wedge shaped teeth of the fixed detector bar and provided with side edges presenting uninterrupted inclines diverging downwardly throughout the height of the teeth at a small angle to the vertical.

In testimony whereof, I have signed my name to this specification.

CLARE H. DRAPER.
